SAND URN

Maurice C. Lumley, Cincinnati, Ohio, assignor to The F. H. Lawson Company, Cincinnati, Ohio, a corporation of Ohio

Application December 31, 1958, Serial No. 53,991

Term of patent 14 years

(Cl. D58—17)

FIG. 1.

FIG. 3.

FIG. 2.

FIG. 4.

The stippling on the drawing represents contrasting colored areas.

I claim:

The ornamental design for a sand urn, as shown and described.
